POSITIVELY OPERATED CONTROL

Charles H. Tindal, State College, Pa., and Lincoln K. Davis, Brockton, Mass., assignors to the United States of America as represented by the Secretary of the Navy

Application May 17, 1946, Serial No. 670,590

3 Claims. (Cl. 114—20)

1

This invention pertains to a hydrostatic device, and more particularly to a device that is attached to a torpedo or similar under-water object and is operable upon reaching a predetermined depth to cause the torpedo to rise to the surface of the water.

Before a torpedo is assembled with an explosive charge it is made to undergo several trial runs for the purpose of determining its operating characteristics. In these runs the torpedo has a water-filled exercise head instead of an explosive-filled war head. The exercise head is of the same shape and of substantially the same weight as the warhead, and, in addition, it contains various means for recording the performance of the missile and for aiding in retrieving it. Air under high pressure is also carried by the torpedo, frequently in a flask section abaft the head. In a common type of torpedo the air in the flask has been consumed to such an extent at the conclusion of the trial run that the pressure thereof falls below a predetermined critical figure, and at this time, a valve is operated to permit the remaining air in the flask to enter the exercise head and expel the ballast water therein.

It happens sometimes that during the trial run the torpedo becomes imbedded in mud or other impediment, due to erratic performance, too deep an initial dive or an irregular bottom. The density of the entire torpedo being therefore at this time still greater than that of water, the missile will sink. Recovery then represents a serious problem. Consequently, it is desirable to incorporate in the exercise head some means to eject the ballast water whenever the torpedo reaches a depth exceeding a predetermined limit. Of course, if the trial run proceeds as was intended, the torpedo will never reach this depth and the buoyancy device will not operate.

The principal object of this invention, then, is the provision of a hydrostatic device for operating on a torpedo when the latter reaches a predetermined depth, for the purpose of forcing the torpedo to rise to the surface.

The invention will be more fully understood with reference to the accompanying drawings, wherein:

Fig. 1 is the top plan of a device incorporating the present invention.

Fig. 2 is a longitudinal elevation of the same structure, parts being shown in section.

Fig. 3 is a side elevation.

Fig. 4 is a cross section taken on line 4—4 by Fig. 2.

2

Fig. 5 is a top plan of a modification incorporating an electric switch.

Fig. 6 is a longitudinal elevation of the modification shown in Fig. 5.

Fig. 7 is a side elevation of the invention shown in Fig. 5.

With reference to the species illustrated in Figs. 1, 2 and 3 of the drawings, the invention comprises a base 11 having a bifurcated central boss 12 formed thereon. To front of the base 11 is fastened a support arm 13, and this support arm 13 secures the front end of a longitudinally expandible "sylphon" or bellows 14. The rear end of the bellows 14 is closed and is movable longitudinally. A double-armed lever 15 is pivoted to the bifurcated central boss 12 so as to be swingable about a horizontal pin 16 in the boss 12. A horizontal pin 17 passes through both arms of the lever 15 at substantially their mid-portion. The bellows 14 is provided with a cylindrical shield 18 that is open at its rear to permit bellows movement but is otherwise continuous over the entire expandible surface of the bellows 14. The front end of the bellows contiguous the support arm 13 is fixed to the said support arm 13 by means of a nut 19. A bellows connector 21 passes through the nut 19 and is in communication with the interior of the bellows 14. The connector 21 is open to the seawater or other external pressure medium in a manner to be more fully described hereinafter. The moveable or rear end of the bellows 14 is held by a plunger 22 on which is formed a central piston-like extension 23. The extension 23 is movably carried by the pin 17 that passes through it. An adjusting screw 24 is threaded longitudinally into the plunger extension 23 for the purpose of varying the effective length of the plunger 22. The upper ends of the double armed lever 15 carry a horizontal pin 25 to which is attached one end of a horizontal coil spring 26. The front end of the spring 26 is fixed to the support 13 by means of an adjusting screw 27 that is threaded through the bellows support 13 and is locked in adjusted position by a nut 28 and washer 29. The spring 26 is under tension so as to force the plunger 22 forwardly against the rear end of the bellows 14. The adjustment of the spring 26 determines the hydrostatic pressure required to operate the device, as will be described hereinafter. The spring 26 is removable, and other springs of greater or less tension may be substituted; thus, one spring may cover the range of 35 to 60 feet of depth; another spring may cover the range from 60 to

90 feet; and a third spring may cover the range from 90 to 120 feet.

The device is provided with a toggle mechanism comprising a lower arm 31 and two upper arms 32, pivoted at the toggle joint 33. The toggle joint 33 is aligned with and movable by the extension 23 of the plunger 22. The adjusting screw 24 hereinbefore mentioned is interposed between the toggle joint 33 and the plunger extension 23 for the purpose of fixing the contact point. The bottom end of the lower toggle arm 31 is pivoted to the boss 12 by a horizontal pin 34, and the upper ends of the toggle arms 32 are pivoted to an actuating lever 35 by a horizontal pin 36. The actuating lever 35 is adapted to swing about a horizontal pin 37 carried by a fixed upright 38 secured to the base 11. An air valve 39 is positioned in the path of movement of the actuating lever 35, and this valve 39 controls the flow of air from the flask of the torpedo to the exercise head. The valve 39 is of such construction that depression of the actuating lever 35 about its fixed pivot 37 will open the valve 39 and permit air from the air flask to enter the exercise head and eject the ballast water therein.

The toggle mechanism also comprises two toggle springs 41 that stretch between the fixed pivot pin 16 in the boss 12 and the movable pivot pin 36 in the lever 35. The springs 41 are under tension, as that in the normal position of the device the toggle mechanism is broken forwardly and the springs 41 serve to bear the toggle joint 33 against the adjusting screw 24. In this position, the actuating lever 35 is elevated and the air valve 39 is in the closed position, shutting off communication from the air flask to the exercise head.

After the torpedo has been launched on its test run, the pressure of the sea water in the bellows 14 will tend to counteract the tension of the horizontal spring 26. If the torpedo falls to such a depth that hydraulic pressure exceeds the predetermined force of the spring 26, the sea pressure will overcome the tension of the spring 26 and will force the plunger 22 rearwardly. The contact screw 24 will consequently push against the joint 33 of the toggle mechanism and urge the said joint 33 rearwardly. As the toggle joint 33 is moved rearwardly, the arms 31 and 32 approach a straight line or dead center position and the toggle springs 41 are subjected to increasing tension. As soon as this position has been passed, the toggle springs 41 will react to snap the toggle joint 33 rearwardly. The horizontal pin 36 will swing in a counter-clockwise direction, and the actuating lever 35 will be depressed by the toggle springs 41. The valve 39 will be forced downwardly to open the communication between the air flask and the exercise head. When sufficient ballast water has been ejected from the exercise head, the torpedo will have attained positive buoyancy and will rise to the surface, where it can be recovered.

A rod 42 may be inserted in each toggle spring 41 to limit the extent of its releasing movement and the downward movement of the actuating lever 35. The set screw 44 locks the pin 36 in the lever 35. A stop screw 45 may be threaded into the boss 11 and held in adjusted position by a nut 46. The lower end of the stop screw 45 bears against an extension of the lower toggle arm 31 in the forward position of the toggle mechanism, for the purpose of limiting the forward movement

of the toggle joint 33 and predetermining the force required to operate the toggle.

The modification shown in Figures 5, 6, and 7 is similar to that already described, except that instead of the air valve, it comprises an electrical circuit for the purpose of actuating an elevator control to cause the torpedo to assume an upward direction.

A plurality of contact leaves 51 are normally biased to closed or conducting relationship with two stationary contacts 52 by a spring 53. When the device is made operative by the increase in hydrostatic pressure, the toggle joint 33 will be pushed rearwardly against the spring 53. The spring 53 surrounds a plunger 54 and the plunger 54 carries the contact leaves 51. It will be seen, therefore, that as the toggle joint 33 is pushed rearwardly against the force of the spring 53 the plunger 54 will carry the leaves 51 out of contact with the stationary members 52. In this case the breaking of the circuit will operate to energize intermediary devices to tilt the torpedo, blow the head, or open the main motor circuit. In another aspect this form of the invention may be so designed that the operation of the toggle switch will close an electrical circuit for the purpose of obtaining the desired effect.

It is understood that the terms horizontal, vertical, front and rear are used only relatively, and that the invention is not to be limited thereby. It is only sufficient that the device be positioned in a portion of the exercise head so that the bellows 14 will be subject to the pressure exerted by sea water at the required depth.

If desired, the hydrostatically operated bellows 14 may be replaced by a solenoid or other operator to cause actuation of the toggle joint 33 under any predetermined condition. For example, the mechanism may be used in exercise runs, with the bellows 14 replaced by such a solenoid, operated through the cyclic circuit in such a manner that after a predetermined time interval, a circuit to the solenoid is closed, causing the toggle joint to snap shut against an air line valve, blowing the head and causing the device to surface.

We claim:

1. A hydrostatically operated control for a torpedo comprising, an expansible chamber one side of which is exposed to a source of hydrostatic pressure, a toggle arrangement disposed with its knee portion in the path of movement of the expansible chamber upon expansion thereof, means for biasing said knee portion toward said expansible chamber, a control actuating lever secured with said toggle so as to be operated when said knee portion is moved by said expansible chamber past the dead center of said toggle to collapse said toggle, said expansible chamber being inoperative to move said knee portion following the collapse of said toggle.

2. A hydrostatically operated control for torpedoes as set forth in claim 1 wherein means is provided to limit the movement of said knee portion toward said expansible chamber.

3. A hydrostatically operated control for a torpedo comprising, an expansible chamber one side of which is exposed to a source of hydrostatic pressure, a toggle arrangement disposed with its knee portion in the path of movement of the expansible chamber upon expansion thereof, means for normally urging said toggle to a position in which said knee portion bears against said expansible chamber, a control actuating lever secured to said toggle so as to be operable upon collapse of said toggle when said knee portion has

been moved through the dead center of said toggle by the force of said expansible chamber, said expansible chamber being inoperative to move said knee portion after the collapse of said toggle, control means operated by said lever to condition the torpedo for retrieval upon increase of hydrostatic pressure beyond a predetermined amount.
